UNITED STATES PATENT OFFICE.

JOSEPH ZEINER, OF MUNICH, GERMANY.

PRIMARY ELECTRIC PENDULUM CLOCK.

SPECIFICATION forming part of Letters Patent No. 363,498, dated May 24, 1887.

Application filed February 15, 1886. Serial No. 191,944. (No model.)

To all whom it may concern:

Be it known that I, JOSEPH ZEINER, of Munich, Germany, have invented a new and Improved Electric Pendulum Clock, of which the following specification is a full, clear, and exact description.

This pendulum clock may be used as a regulator-clock for the room, or as a normal clock for moving a system of secondary electric dial-trains. In the drawings a clock of the latter kind is represented, the dial-hands and wheels of the dial-train being omitted.

Figure I represents the upper and Fig. II the lower part of the pendulum, in elevation. Fig. III is a ground plan of the most essential parts. Figs. IV and V are details of the contact parts *o l*. Figs. VI, VII, VIII, IX, X, and XI show modifications of the invention.

In Fig. I the pendulum-rod is marked *P*, acting against the toothed wheel *R* to turn the same on its axis *A* one tooth at every double vibration by means of the pawl or lever *b*. This wheel *R* is kept in its position during the back motion of the pendulum and pawl by friction of a spring, *f*, which glides on the hub or tube *a*, connected with wheel *R*. It is evident that certain points of wheel *R*—*e. g.*, the edges of the teeth—must, when at rest, occupy different positions to a fixed point lying outside of the wheel, according to the greater or smaller arc of oscillation of the pendulum and to the greater or smaller motion toward the right of the tooth pushed forward. This fact has been utilized in the present case to produce a self-acting closing of the circuits. The wheel *R* has at the back six pins, *t*, having semicircular cross-sections.

H is a lever pivoted at *d* and pressed by a weight, *G*, against a regulating-screw, *n*, placed near the lower end of this lever. Upon a horizontal axle or pin attached to this lever *H* a small lever, *i*, turning freely, is placed, provided with an inclined plate, *k*, at one end and a small protruding plate, *p*, at its other end, nearest the pendulum.

On the rod *P* the hook-shaped pin *q* is attached, provided with a sharp edge at its under side.

The motion of the pendulum is effected in following manner: After the same has been set to oscillate, the wheel *R* is pushed around one

tooth at every double oscillation of the pendulum. At the same time the pins *t* glide, one after the other, over the incline plane *k*, which causes every time the lifting of plate *p* to the level of pin *q*. When the oscillations of the pendulum are of sufficient length, the pin *t* will move a little distance beyond *k*, allowing the left-hand part of the lever *i* (being heavier) to fall back again before pin *q*, at its return, can seize hold of plate *p*. Whenever the arc of oscillation of the pendulum decreases to a certain point, the pin *t* does not pass entirely beyond *k*, and the left-hand part of the lever *i* will be held in its raised position. Upon the next oscillation of the pendulum toward the left the sharp edge of pin *q* engages a notch on the plate *p*, thereby connecting the lever *H* with the pendulum, when the levers *i H* will be drawn toward the left, so that a pin, *o*, attached to lower end of lever *H*, will glide over the end of spring *l* and close the circuit. The current passes then from battery *B'* over binding-post 1, axle *d*, lever *H*, pin *o*, spring *l*, binding-post 5 to the solenoid *Z*, Fig. 2, and back to battery *B'*.

As soon as the current is created in the solenoid *Z*, the iron core *E*, attached to the pendulum, will be drawn in, and thus a new impulse is given to the pendulum. When this new impulse is given to the pendulum, the oscillation of the same will be increased, whereby the pin *q* will leave again the notch on the plate *p*, and thus disconnect the lever *H* from the pendulum *F*. The lever *H*, with pin *o*, is drawn so far to the left that the pin *o* leaves the end of spring *l*, when the current will be again broken. The spring *l*, which had been pressed downward by pin *o*, resumes its former position, so that at the following oscillation of the pendulum toward the right the pin *o* will glide over the lower surface of the inclined end of spring *l*. This lower surface is coated or covered with non-conducting material, whereby the circuit will be broken. In the same way the contact is broken in the modifications shown in Figs. VI to XI before the pendulum has commenced its backward motion. After the pendulum has received the necessary impulse, the pins *t* will glide over *k* until a new impulse becomes necessary. The lateral arrangement of pivot *d* of lever *H* has for its object to depress the axle *i*

during the motion of the lever toward the left, so that the parts *k* and *t* will not come into contact.

The parts of contact *o* and *l* are shown in the ground plan, Fig. IV. The flat spring *l* may be replaced by a bent wire, as represented in Fig. V. The number of pins *t* may be fixed, at pleasure, within a certain limit. Instead of the pins, other parts of the wheel, even the teeth of the wheel, may be used. In place of imparting motion to the pendulum by a solenoid and core, an electro-magnet and armature may be employed.

The apparatus of contact for the current to move the secondary electric dial-train is constructed as follows: Wheel *R* has the same number of teeth as the oscillations of the pendulum during a minute. Therefore half a revolution takes place every minute. The tube *e* is permanently and conductively connected with wheel *R*, Fig. III, and carries a hard-rubber tube, *r*, upon which the brass tube *a* is slipped. The tube *a* is connected with a thin plate or lamella, *y*, which is attached to but isolated from edge of wheel *R*, and carries on its end the pin *x*. Opposite pin *x* a second pin, *z*, is attached to and in electric contact with wheel *R*. The parts *a y z* are thus isolated from parts *A e R c* by interposed hard-rubber parts. Above and below the wheel *R* the contact-springs *e* and *g* are attached, so that the pins *x* and *z* glide over them simultaneously when in their vertical position, Fig. I. Now, when the pin *x* is in contact with spring *e* and the pin *z* with the spring *g*, the current issues from the battery *B*, goes over binding-post 3 and the parts *f a y x e* to binding-post 2 and to the wire *M*, leading to the dial-train, and returns by way of wire *N*, binding-post 4, and parts *g z R c A* to *B*; but when *z* is in contact with *e* and *x* with *g* the current will run from *B* over binding-post 3, spring *f*, parts *a y x g* to the dial-train wires, and will return by binding-post 2, parts *e z R c A* to the battery *B*. Consequently a current of alternate directions is transmitted every minute through the dial-train circuit.

The above-described construction of an electric pendulum clock, which is illustrated in Figs. I to III, admits of different modifications.

Fig. VI shows the essential parts of a pendulum in such an arrangement that the contact part *o'* is in rigid connection with the pendulum. The one-arm lever *m'* has its fulcrum *d'*, and is pressed by a spiral spring against an adjusting-screw in the direction of the arrow. This lever carries an inclined plane, *k'*, and the contact-spring *l'*.

When the pendulum oscillates toward the right, the lever *m'* and spring *l'* are forced by the pin *t'* out of the position shown in dotted lines into the position shown in full lines whenever the oscillation of the pendulum is not sufficient to cause the pin *t'* to pass the end of the inclined plane *k'*. The lever *m'*, with spring *l'*, remains in that position, so that during the succeeding oscillation of the pendu-

lum toward the left the pin *o'* will glide upon the inclined plane at the end of the spring *l'* to close the circuit, as above described, and, passing then over the edge of said inclined plane, returns along the lower isolated side of said inclined plane. The current travels over the suspending-springs of the pendulum and the axle *d'* of the lever. The contact parts *o'* and *l'* of this and the following figures have the form shown in Fig. IV in ground plan.

In Fig. VII a two-armed lever is used, capable of oscillating upon an axle, *d'*. The left arm of this lever is formed by spring *l'*, provided with a small weight. The closing of the current is produced the same as in Fig. VI by pin *o'*, except that during the time the current is closed the right-hand arm of this lever *m'* is pressed against pin *t'*.

In the arrangement in Figs. I and III the pins *t* cause a temporary connection of a lever with the pendulum, and the consequent motion of a contact part ordinarily at rest, while with the modification shown in Figs. VI and VII an approach of a fixed contact part is produced with the pendulum. In the first case the contact is produced directly through the motion of the contact part. In the second case the motion of the contact part has for its object, primarily, to bring the parts in such a position that a second moving part must come into contact with it; but it is clear that, instead of producing the motion of a contact part by pin *t*, the motion of parts which are loosely connected with the pendulum may be checked. These modifications are shown in Figs. VIII, IX, and X.

Fig. VIII is a front view, and Fig. IX a plan, of an arrangement of the essential parts by which a direct stopping of one or both contact parts that are connected to and oscillate with the pendulum may be produced. The outer circumference of wheel *R'* is placed, as in Fig. III, in the plane of oscillation of the pendulum, while the web or supporting-arms are attached laterally to the circumference and placed behind the same. Upon the inner edge of the ring which is thus produced notched pins *t'* are placed in a radial direction. The vertically-placed spring *u* carries a pin, *o*, bent angular, and a movable horizontal-arm, *v*. This arm passes laterally in front of the ring *R'*, and is then bent backward toward the web of the wheel with an edge at its lower side. When the pins *t'* do not advance far enough, this edge engages, during the motion of the pendulum toward the left, a notch made in the pin *t'*, thus holding the fixed spring *u* while the pendulum retreats when the contact-pin *o* glides over the inclined end of spring *l'* and closes the circuit.

During the succeeding oscillations of the pendulum toward the right the pin *o* returns over the isolated part of *l'* to its old position. By the motion of wheel *R'* the arm *v* moves a little upward, but drops as soon as the pendulum has moved sufficiently far to the right.

A further construction for checking the mo-

tion of a contact part is shown in Fig. X, where w represents a two-armed lever having a contact spring, t^4 , provided with a weight attached. The vertical arm of the lever w lies loosely against a plate, h , secured to the pendulum-rod. The horizontal arm of the lever w carries at its end a projecting pin, s , flat on top, and the pins t^4 , attached to the wheel, are also flattened to correspond with the flat part 10 of the pin s . When the pendulum is oscillating, the lever w , as well as the spring t^4 , is made to oscillate upon the axle d^4 on account of the vertical arm of lever w resting against plate h .

15 The contact-pin o^4 , secured to the pendulum-rod, moves toward the right from the inclined end of the spring t^4 , so that ordinarily no contact of the parts takes place. If, however, the arc of oscillation is reduced to a certain 20 minimum, so that the pin t^4 does not advance far enough, then the pin s comes in contact with pin t^4 while the pendulum oscillates toward the right, and the lever w and spring t^4 will be held stationary, and the spring t^4 will 25 remain in its raised position, as shown in dotted lines, when the pin o^4 will pass over the inclined part of spring t^4 , and thus close the circuit. Before the end of its motion toward the left the pin o^4 will leave the end of spring 30 t^4 , the circuit is again opened, and pin o^4 returns over the lower isolated face of spring t^4 .

In Fig. XI an arrangement is shown which has for its object to alter the position of an oscillating contact part in relation to a permanent one. The arrangement of the wheel and of the pin t^5 is the same as in Fig. VIII. The arm v' is also arranged in a similar manner as the arm v in Fig. VIII, excepting that it is carried by a vertical arm of a bent lever, w' . 35 This lever is pressed by spring f' against the pendulum-rod. The horizontal arm of this lever carries at its end a pin, o^5 , and at a short distance therefrom the contact-spring t^5 is placed. The dotted line indicates the way 40 usually described by pin o^5 . If, however, during the oscillation of the pendulum toward the left, the arm v' catches into pin t^5 , the pin o^5 will simultaneously move downward, and will describe a much more inclined way than 45 the one shown in dotted lines, and will then come in contact and glide over spring t^5 to close the circuit, returning over the isolated rear side of the spring in the manner above 50 described. It may be mentioned that this downward motion of the horizontal arm of lever w' , or the upward motion of an addi-

tional arm directed toward the left from the fulcrum, may be utilized to cause the motion of a contact part normally at rest.

In the arrangement shown in Figs. VIII to 60 XI the pendulum, apart from the task of pushing forward wheel R , swings perfectly free until a contact intervenes.

The influence on the pendulum caused by the resistance of the wheel can be reduced to 65 a minimum, particularly if the contact apparatus for the line-current be omitted, and in any case is less than when the counting of the oscillations of the pendulum is done by producing a contact at every double oscillation. 70 It is particularly worthy of notice that in the present construction all the contacts are gliding contacts, and that the contact-pins glide over a proportionately long plane, leaving it only at the edge. With this arrangement an 75 appliance for removing the interrupting spark is completely superfluous, and the contact parts will stand a number of years' wear before it will be necessary to replace them by new ones. 80

The movement of the hands of the controlling or primary clock may be effected by ordinary wheel-gear or by two opposite pins being placed on the front side of the wheel R , which lifts every minute a lever provided with an 85 arm that pushes a minute-wheel forward one tooth.

The advantages of this pendulum clock are as follows: The pendulum is perfectly free in its oscillation, the contact ensues only when 90 the arc of oscillation has reached a certain minimum limit, while the work the pendulum has to do is extremely insignificant.

I claim as my invention—

1. The combination of a pendulum carrying 95 a pawl or lever, b , and pin q with tooth-wheel carrying pins t , and with a pivoted lever, H , interposed between the pendulum and tooth-wheel, carrying lever i and contact-pin o , and with fixed spring l , substantially as specified. 100

2. The combination of a pendulum carrying a pawl or lever, b , and a contact part, and a tooth-wheel carrying pins, with a lever and with a fixed springing contact part having 105 part of its lower surface coated or covered with non-conducting material, substantially as specified. 110
